(57) **CLAIM**

The ornamental design for a surgical hook for a cricothyrotomy, as shown and described.

DESCRIPTION

FIG. 1 is a first perspective view of a surgical hook for a cricothyrotomy according to our new ornamental design; FIG. 2 is a second perspective view thereof;

FIG. 3 is a front view thereof;

FIG. 4 is a rear view thereof;

FIG. 5 is a side view thereof, wherein the opposite side view is a mirror image of FIG. 5;

FIG. 6 is a first end view thereof; and,

FIG. 7 is a second end view thereof, opposite to the first end view.
